KEY LOOP SUPPORTING PLATE

Morgan V. Duell, Oakville, Conn., assignor to
 Scovill Manufacturing Company, Waterbury,
 Conn., a corporation of Connecticut

Application January 20, 1951, Serial No. 207,023

2 Claims. (Cl. 70—456)

1

This invention relates to key loop supporting plates and particularly to an improved retainer member for holding and permitting the removal of the key holder hooks or loops from the holder support or plate.

The invention pertains particularly to that type of key holder plate formed with a barrel or tubular portion having a series of transverse slots merging into enlarged openings, through which the heads of key loops may be assembled and removed, and wherein a retainer or holder bar is employed for closing off the enlarged openings in retaining the key loops in the plate.

The principal object of this invention is to provide a key retainer plate made of only two parts and having all the advantages of the more complex holder plates in providing spring means for actuating the retainer bar, also having provision to permit the assembly of the key loops into the plate without the necessity of having to manually operate the retainer bar and to automatically discharge the key loops by the manual operation of said retainer bar.

A further object is to so construct and form the key holder plate and the retainer bar that they can be assembled and disassembled from each other without any subsequent forming operations by merely having the parts properly interfitted and sprung into and out of assembled engagement.

A still further object is to provide a key holder plate of the above character such that it can be made of relatively thin steel stock and hardened to provide suitable spring temper to the plate out of which a spring tongue may be formed of sufficient strength to actuate the retainer bar.

These and other objects and features of the invention will appear from the following description thereof in which reference is made to the figures of the accompanying drawing, in which:

Fig. 1 is a front plan view of a key retainer plate showing a single key loop associated therewith.

Fig. 2 is a back plan view of the key holder plate.

Fig. 3 is a right end view of the plate.

Fig. 4 is a sectional view taken along the line 4—4 of Fig. 1.

Fig. 5 is a sectional view taken along the line 5—5 of Fig. 1.

Fig. 6 is a view similar to Fig. 5 showing how the free edge part of the barrel portion of the plate is sprung outwardly to permit the assembly and disassembly of the retainer bar.

Fig. 7 is a perspective view of the retainer bar per se, and

2

Fig. 8 is a front elevation of the key case in open position showing the holder plate attached thereto.

Referring now to the drawing in which like reference numerals denote like parts throughout the several views, the numeral 10 refers to a cover or leather folder to which is secured the flattened base part 11 of a key holder plate 12 adjacent one edge of said cover 10 as by tubular rivets 13 passing through suitable openings 14 in the base part 11.

The holder plate 12 is preferably made of high carbon steel and hardened for reasons as will appear later. The fact that this plate is so designed as to permit it to be made of high carbon steel permits the use of a much thinner stock than is customarily employed in key holder plates, and therefore, results in a saving in the cost of the material used.

20 The plate 12 adjacent the upper longitudinal edge of the base part 11 is formed with a relatively narrow wall 15 positioned substantially at right angles to the base part 11. Extending from the upper end of the upright wall 15 is an inclined wall 16 supporting on its outer end a tubular part 17. The opposite end of the tubular part 17 extends into a flattened section 18 that normally lies in a plane common with the base part 11. A series of circumferential narrow slots 19 are provided in the tubular part 17 and terminated at one end in enlarged openings 20 positioned adjacent the flattened section 18.

The keys are attached to the plate 12 by means of the usual form of key loops 21 that have shanks 22 capable of having free movement in the slots 19 and enlarged heads 23 on one end capable of passing through the enlarged openings 20 but not through the slots 19.

In order to retain the key loops 21 attached to the tubular part 17 provision is made of a locking strap or retainer bar 24. The bar 24 is located within the tubular part 17 and is held there in place by means of a pair of spaced T-shape lugs 25 each consisting of a transverse head 26 on the end of a connecting neck 27.

In order to interfit the T-shape lugs 25 into the holder plate 12, the base part 11 is provided with elongated openings 28 suitable to loosely receive the transverse heads 26 while the upright wall 15 is provided with slots 29 joined into said openings 28 and dimensioned to receive the lug connecting necks 27. In the normal assembled position of the retainer bar 24, as shown in Fig. 3, the inside edges 30 of the T-shape lug heads 26 are positioned against the outside of the upright wall 15 to prevent lateral movement of the

retainer bar 24 within the tubular part 17 and at the same time allow the retainer bar 24 to pivot within said tubular part 17.

The retainer bar 24 is normally positioned to lie flat against the top surface of the flattened section 18 and positioned to partially close off enlarged openings 20 so as to prevent the key loop heads 23 from passing therethrough. The bar 24 is normally held in this position by means of an elongated spring tongue 31 cut out from the base part 11 with a suitable U-shaped clearance slot 32 thereabout to allow free movement of said tongue. The outer end of said tongue is slightly offset as at 33 and adapted to rest against the upper surface of said retainer bar 24. (Note 15 Fig. 4.)

The retainer bar 24 is provided with a projection lug 34 at one end serving as a handle that is exterior of the tubular part 17 for operating said retainer bar 24. As noted in Figs. 1 and 2 one edge of the lug handle 34 operates in a recess 35 provided in the adjacent end of the tubular part 17, which slot controls the amount of stroke that the bar 24 may pivot within the tubular part 17.

As brought out in the objects of this invention, one of the principal features of this holder plate is that the retainer bar may be assembled into the tubular part without any subsequent forming assembly operations. In order to assemble the retainer bar 24, the tubular part 17 is sprung so that the flattened section 18 provides for a clearance space between its free end and the adjacent end of the base part 11 as at 36 (see Fig. 6) which will allow the retainer bar 24 to be slipped thereinto place and positioned so that the transverse heads 26 of the T-shape lugs 25 will align with the elongated openings 28 in base part 11 and the connecting necks 27 in line with the slots 29. In allowing the tubular part 17 to spring back to its normal position the flattened section 18 will elevate the retainer bar 24 into its assembled position with the T-shape lugs engaged within their respective openings and slots 28 and 29.

It is to be noted from Fig. 7 that the transverse heads 26 of the T-shape lugs are slightly biased to the plane of the retainer bar 24 and connecting necks 27. This is in order to position the heads 26 slightly above the plane of the base part 11 so as to prevent the heads 26 from slipping out of the elongated openings 28 coincident with the pivoting operation of the retainer bar 24.

In order to assemble the key loops 21 to the holder plate 12, the enlarged head 23 on the loop shank 22 is first aligned with the enlarged opening 20 from the underside of said plate 21, and then forcing it upwardly through the opening 20 will cause the bar 24 to pivot against the influence

5
10
15

of the spring tongue 31 and allow the key loop head 23 to slip into the tubular part 17. After the enlarged head 23 has cleared the outer edge of the bar 24, as seen in Fig. 5, the bar 24 will automatically swing back to its closed position to partially cover the opening 20 so as to prevent the escape of said key loop 21 from the retainer plate. The key loops 21 with or without keys will normally lie against the upper surface of the base part 11. To remove the key loops 21, it is only necessary to swing them to an upper position and by lifting the handle lug 34 the bar 24 will be swung to open position to clear the enlarged openings 20 whereupon the key loop will automatically drop out through said enlarged openings 20.

While I have herein described and upon the drawing shown an illustrative embodiment of the invention, it is to be understood that the invention is not limited thereto but may comprehend other constructions and arrangements without departing from the spirit of the invention.

What I claim is:

1. In a key holder device to which key loops having enlarged heads may be removably secured comprising a plate member having a flat base part adapted to be attached to a flexible support, a narrow wall extending upwardly from one edge of said base part, an inclined wall supported by said narrow wall and extended into a tubular part with the free end of the latter terminating in a flat section on a plane common with said base part and having its free edge adjacent said narrow wall, said tubular part having spaced circumferential slots terminating in enlarged openings adjacent said flat section and through which openings the key loop heads may be inserted and removed, a retainer bar positioned in said tubular part, means hingedly connecting said bar to said narrow wall and permitting pivotal movement of said bar in said tubular member, spring means normally urging said bar against said flat section in position to partially close off said enlarged openings, and handle means for operating said bar against the influence of said spring.

2. In a key holding device as defined by claim 1 wherein said hinged connecting means is in the form of T-shaped lugs projecting from one longitudinal edge of said bar and having interfitted engagement in complementary slots provided in said base part and narrow wall.

MORGAN V. DUELL.
